UNITED STATES PATENT OFFICE.

JOSEPH G. KONVALINKA, OF ASTORIA, NEW YORK.

IMPROVEMENT IN WATCH AND LOCKET CASES.

Specification forming part of Letters Patent No. 56,575, dated July 24, 1866.

To all whom it may concern:

Be it known that I, JOSEPH G. KONVALINKA, of Astoria, in the county of Queens and State of New York, have invented a new and useful Improvement in Watch and Locket Cases; and I do hereby declare that the following is a full and exact description of the construction and operation of the same, reference being had to the accompanying drawings, and to the letters of reference marked thereon.

The subject of my improvement is a certain mechanism for the operation of the spring-cap of the case.

The mechanism that has hitherto been in general use for this purpose consists of two case-springs, which are hidden inside the case. The situation and construction of these springs cause considerable inconvenience and trouble, to obviate which is the object of this improvement.

The principal peculiarity of my improvement consists in applying the mechanism for the operation of the spring-cap externally upon the case, and in this respect it differs essentially from the above-mentioned case-springs, which are hidden inside the case.

Figure 1 is a front elevation of the case. Figs. 2 and 3 are side elevations of the case, of which Fig. 2 represents the cap shut, and Fig. 3 represents the cap open. Fig. 4 represents an elevation of the bottom of the case as seen when the case is lying on the table. Fig. 5 is a section of the head C and knob E and an elevation of the parts hidden inside of said head C. Fig. 6 is a side section and elevation of the same parts. Fig. 7 represents the parts of Fig. 5 detached, in order to show more plainly each of these parts. Figs. 5, 6, and 7 are represented on an enlarged scale—say double the linear dimensions of Figs. 1, 2, 3, and 4.

The figures in the drawings are represented in colors, in order to show more plainly the different parts, and not to indicate of what material these parts should be made. These parts can be made of various different materials, such as are otherwise used in the arts for similar purposes. I consider the mechanical construction and operation of these parts the subject of my improvement and Letters

Patent, of whatever material these parts may be made.

A is a pin fastened to the frame or rim B of the case. C is the head of the pendant or handle. This head is movable; it slides up and down.

D is a spring coiled around the six-pin A and inclosed within the movable head C. Said spring serves the purpose to press the head C down—i. e., toward the case.

At the top of the pin A is screwed or otherwise fastened the top-piece or knob E. This top-piece keeps down the spring D, and serves also as a push-knob.

F is a cross-pin which passes through the top of the pin A and through the knob E, in order to keep said knob securely in its position.

At the foot of the head C is the catch G, which serves the purpose to lock the cap H when it is shut.

If the edge of the cap itself is not of a suitable shape, so as to afford a sufficiently secure hold to the catch G, a little notch is cut or filed into this end, near the edge of said cap, as shown at J.

K K are two pins fastened to the frame or rim B of the case, and projecting in corresponding cavities in the bottom of the head C, in order to prevent said head from turning.

The operation of these parts is as follows: In shutting the cap H the head C is raised until the edge of the cap passes under the catch G, and thus the cap is locked. When it is desired to open the cap H, it is effected by pressing with the thumb upon the knob E, while the ring L is held in hand, or by pulling at the ring L. In this way the head C and catch G are raised, and thus the cap H released or unlocked. At this instant the cap is thrown up by the throw-up spring.

M represents the throw-up spring, which is bent externally over the cap H. It is attached by means of a joint, N, or otherwise, in a suitable manner, to the case.

O is a bridge fastened by means of screws or otherwise upon the cap H. It serves the purpose to keep down the spring M, allowing said spring to slide beneath.

P is the head of a screw or rivet. When the cap H is thrown up the end of the spring M

strikes against said head P, and thus prevents the cap from opening too far, and protects the joint of the cap against breaking.

What I claim as new and of my invention, and desire to secure by Letters Patent, is—

1. The movable head C, fitted or mounted on a fix-pin A, substantially as and for the purpose above specified.

2. The spring D, in combination with the movable head C and fix-pin A, and operating substantially as and for the purpose above specified.

3. The catch G, when it is movable—i. e.,

sliding up and down—and operating substantially as and for the purpose above specified.

4. The spring M, bent externally over the cap H, and operating substantially as and for the purpose above specified.

5. The bridge O, fastened externally upon the cap H, substantially as and for the purpose above specified.

JOSEPH G. KONVALINKA.
